UNITED STATES PATENT OFFICE.

GEORGE H. REIMER, OF FULTON, ILLINOIS, ASSIGNOR TO PATENT NOVELTY COMPANY,
OF FULTON, ILLINOIS, A CORPORATION OF ILLINOIS.

RECEPTACLE AND LOCK THEREFOR.

Application filed March 11, 1922. Serial No. 542,908.

To all whom it may concern:

Be it known that I, GEORGE H. REIMER, a citizen of the United States, and a resident of Fulton, Whiteside County, Illinois, have invented a certain new and useful Improvement in Receptacles and Locks Therefor, of which the following is a specification.

This invention relates to receptacles having locks, and more particularly those having permutation locks, such as document cases or other metal boxes, and receptacles or other things of like character to which locks of this kind are applicable.

Generally stated, the object of the invention is to provide a novel and improved construction whereby a receptacle or other enclosure may be provided with a simple and effective permutation lock which can be manufactured at a comparatively small cost of production, and which will at the same time be reliable and attractive in appearance.

To the foregoing and other useful ends the invention consists in matters hereinafter set forth and claimed and shown in the accompanying drawings in which—

Figure 1 is a top view of a document receptacle (it can be used for any desired purpose) having a permutation lock embodying the principles of the invention.

Figure 2 is a front elevation of said box or receptacle.

Figure 3 is a transverse section on line 3—3 in Figure 1.

Figure 4 is a detail vertical section on line 4—4 in Figure 3.

Figure 5 is an enlarged bottom view of said lock.

Figure 6 is a section, on a larger scale, on line 6—6 in Figure 5.

Figure 7 is a view similar to Figure 6, showing the parts in different positions.

Figure 8 is a view similar to Figure 5, with certain parts removed, and showing the pivoted or swinging member in a different position.

Figure 9 is a detail view of certain parts.

Figure 10 is a view similar to Figure 5, but with the parts thereof in the positions in which they are shown in Figures 7 and 8.

Figure 11 is a detail view of some of the elements of the lock, showing the different tumblers in plan view.

Figure 12 is an edge view of the parts shown in Figure 11.

As thus illustrated, the invention comprises a box or receptacle of general rectangular form or shape, as shown, having a cover 1 and a bottom or body portion 2 connected together at the rear edge of the box by hinge 3, the cover having an internal lug 4 at its front edge to connect the spring 5 which is flexibly secured to the bottom portion of the box by rivets 6, and which is provided with a push button 7 projecting from the front of the box. Said spring 5 has an opening 8 to engage the lug 4, and by pressing inward on the push button 7 this spring can be disengaged from said lug, thus permitting the box to be opened. When the box is closed, the latch snaps into place, inasmuch as the spring is forced out by the lug 4 until it enters the opening 8 in said spring.

The said lock shown in the drawings is arranged to control the spring 5, and when the box is locked the spring 5 cannot be forced inward. Said lock has a plate 9 which is secured to the inside of the cover by rivets 10, thereby to close the opening 11 in the top of the cover, said opening having portions of the sheet metal disposed at each side thereof to form recesses 12 for the outer heads of said rivets. The plate 9 has the necessary indications or graduations on the upper surface thereof, as shown in Figure 1, and is provided with a central opening for the post 13 which is rigid with the handle 14, the other end of the lock having a hand 15 for use in accurately positioning the handle relatively to said indications or graduations on the outer face of the lock.

The lower end of the post 13 is riveted over and supports a guard plate 16 which is upturned at its edges to partially inclose the mechanism of the lock. The lower metal washer 17 is a tumbler which is rigid with the post 13, and is provided with the upstanding pin 18 and with a flat spot 19 at one edge thereof. On this tumbler is a washer 20, and on this washer is the next tumbler 21 which is loose on the tubular sleeve 22 that incloses the center post of the lock. This tumbler 21 has a notch 23 in one edge thereof, and has an upstanding pin 24 and a downwardly projecting pin 25, it be-

ing understood that Figure 11 shows the lower surfaces of the tumblers. On the tumbler 21 is a washer 26, and on this washer is the third tumbler 27 which has its 5 lower surface provided with a pin 28, and which has a notch 29 in one edge thereof. The three tumblers are shown upside down in Figure 12, as in Figure 11, as stated, the lower surface of each tumbler is shown; but 10 when in use, and when the box is right side up, when the cover is closed, the pins 18 and 24 extend upward, while the pins 25 and 28 extend downward. The portion of the lock which keeps the spring 5 from being pressed 15 inward, when the box is locked, comprises a pivoted member 30 having a depending arm 31 to engage said spring, and having a shorter depending arm 32 for engaging the tumblers of the lock, the two arms being 20 spaced apart a distance as shown, said member having a vertical pivot 33 by which it is swingingly mounted on the under side of the plate 9, previously mentioned. A spring 34 is suitably applied to the arm 30 to bear 25 upon the under surface of the plate 9 and to provide the necessary friction for holding the arm 30 against being jarred out of position.

With the foregoing construction, it will 30 be seen that rotation of the handle 14 will cause the pins 18, 24, 25 and 28 to communicate the rotary motion from one tumbler to the other, and the location of these pins will determine the combination of the lock. 35 When the handle is in the position shown in Figure 6, and the tumblers are as shown in this view of the drawings, the box is locked, for in such case the arm 31 is held in position to prevent inward movement of 40 the spring 5, (see the dotted position of this arm 31 in Figure 3) so that the spring cannot be pushed inward by the push button 7 disposed on the front edge of the box. However, by swinging the handle 14 around, 45 first one way and then the other, the tumblers are finally moved into the position which they have in Figure 7, and in such case the notches 23 and 29 and the flat spot 19 are opposite the arm 32, and this will permit 50 inward movement of the arm 31, inasmuch as the arm 32 can move into said notches of the tumblers, as shown in Figure 7, (also as indicated in Figures 5, 8 and 10), thus permitting the box to be unlocked. 55 Of course, the positions of the pins 18, 24, 25 and 28 can be changed on the tumblers for different boxes, so that no two boxes will have the same combination.

From the foregoing it will be seen that 60 a very simple and inexpensive form of permutation lock is provided for a document case or for a box of any kind, or for receptacles or inclosures in general. However, the lock as applied to the sheet metal box 65 as shown and described, and as constructed

for this purpose, not only tends to reduce the cost of manufacture, but also tends to ensure both durability and reliability in the use and operation of the lock, as well as attractiveness in the appearance of the device as a whole. 70

It will be seen that the opening 11 is countersunk, so that the plate 9 is disposed a distance below the top wall of the box, and whereby the handle or rotatable member 14 75 is flush with the top of the box, but is rotatable on the dial formed on the outer surface of the plate 9 to unlock the box. In this way, the box can be pushed into a pigeon-hole in a vault, or into a desk, without catching on other things. Also, the push button 7 engages the spring 5, as previously explained, and is either rigid therewith or separate therefrom, as may be desired. For example, this push button may be formed 80 of sheet metal, and can simply be a small cup like element with its rim interposed between the spring and the edges of the opening in the front of the box through which the button extends far enough to be 85 pushed inward in the desired manner.

What I claim as my invention is—

1. In permutation lock mechanism, the combination of a top wall with an opening 90 therein, a plate secured to the inner side of said wall, to close said opening, with indicating means on the outer surface of said plate, a rotatable member forming a controller on the dial thus formed by the outer surface of said plate, and inclosed devices controlled by said rotatable member, said opening being countersunk and said rotatable member being flush with the outer surface of said wall, in combination with other walls combining with said first mentioned wall to form a box, and an automatic latch for said box controlled by said devices, adapted for inward movement toward the axis of said member to unlock the box, together with a push button on the front side of the box and independent of said controller and adapted for operating said latch to open the box. 100

2. A structure as specified in claim 1, said latch comprising a spring having an opening, and a lug for engaging said opening in the spring, said push button engaging a portion of said spring below said lug. 115

3. A structure as specified in claim 1, said latch comprising a spring, and said devices comprising an arm adapted to engage said spring to prevent opening of the box. 120

4. In permutation lock mechanism, the combination of latching means, a pivoted member having an arm for engaging said latching means, tumblers having notches to receive said member, thereby to permit operation of said latching means, means forming a controller for operating said tumblers without disturbing the locking position of 125 130

said member, and separate means independent of said controller and adapted for manually moving said latch and thereby pushing said member into said notches of the tumblers, thereby to unlock said latching means.

5. A structure as specified in claim 4, said

latch comprising a spring having an opening therein, and a lug for engaging said opening, one end of said spring being adapted to engage said arm, and said means for operating said latching means comprising a push button engaging said spring. 10

GEO. H. REIMER.
